The ornamental design for a bottle, as shown and described.

DESCRIPTION

FIG. 1 is a front, right perspective view of a bottle showing our new design;

FIG. 2 is a front view thereof;

FIG. 3 is a right side view thereof;

FIG. 4 is a rear view thereof;

FIG. 5 is a left side view thereof; and,

FIG. 6 is a top view thereof.

The uneven-length broken lines represent unclaimed boundaries of the claimed design. The even-length broken lines showing the remainder of the bottle are for environmental purposes only and form no part of the claimed design.
